UNITED STATES PATENT OFFICE.

BEULAH L. RAINS, OF DUNLAP, MISSOURI, ASSIGNOR OF ONE-FOURTH TO AUGUSTA G. SIMPSON AND MARTHA JANE NEWMAN, BOTH OF ALLIANCE, NEBRASKA.

ADJUSTABLE SHADE AND CURTAIN BRACKET.

Application filed May 1, 1924. Serial No. 710,336.

To all whom it may concern:

Be it known that I, BEULAH L. RAINS, a citizen of the United States, residing at Dunlap, in the county of Grundy and State of Missouri, have invented certain new and useful Improvements in Adjustable Shade and Curtain Brackets, of which the following is a specification.

This invention relates to improvements in adjustable shade and curtain brackets, and particularly to a bracket for supporting a shade roller adjacent a window casing, supporting curtains inwardly of the shade roller, and draperies inwardly of the curtains.

An object of the invention is to provide a pair of shade roller brackets adapted to be secured to a window casing, and provided with suitable means for removably supporting a shade roller therein, and the outer end being provided with an adjustable connection between the brackets, to provide a drapery support, and having an adjustable curtain support suspended from said roller brackets intermediate the ends thereof, so that curtains may be supported adjacent the shade of the roller carried by the bracket, and draperies supported at the inner ends of the bracket on the adjustable drapery supporting members for overhanging the curtain and concealing the supporting structure therefor.

Another object of the invention resides in providing a curtain and drapery supporting bracket of the class mentioned, wherein a pair of bar members are provided with feet to be secured to a suitable window casing in spaced relation, at one end thereof, and adapted to project inwardly in said casing, and which mount at the inner ends bar members which are pivotally connected to said shade roller brackets, and adjustably connected with each other, to provide a drapery supporting member between the shade rollers, while another pair of bars are adjustably connected together and suspended from the brackets for the shade rollers, outwardly of the bars for supporting the draperies to provide a supporting structure, for curtains.

Another object resides in providing a device of the character described, wherein a pair of bar members are pivotally connected to shade roller supporting brackets, one of which is provided with an outstruck pro-

jection, extending longitudinally thereof adapted for a sliding interfit in a slot formed in the other bar, in order that a pair of clamp members may be interposed between the struck out projections and the slotted bar, for retaining both bars in connected relation, but permitting lengthwise adjustment of said bars.

The invention also comprehends other objects and improvements in the details of construction and arrangement of the parts, which are more particularly pointed out in the following description and claims, directed to the preferred form of the invention, it being understood however, that variations may be made in this structure, without departing from the spirit and scope of the invention as claimed.

In the drawing, forming a part of this application:

Figure 1 is a detail perspective view of the shade roller and drapery supporting structures constructed according to this invention.

Figure 2 is a longitudinal transverse section through the adjustably connected bar members, illustrating the manner of adjustably connecting said bars.

Fig. 3 is a vertical sectional view taken on line 3—3 of Fig. 1, illustrating the manner of forming an assembly, with the bar members for the adjustable connections.

Figure 4 is a detail view of one of the bar members which is provided with an outstruck or offset projecting tongue.

Figure 5 is an enlarged detail view of the member, showing the slot formation thereof.

A pair of shade roller supporting brackets 1 are formed with bar members provided at one end with feet 2, adapted to be secured to a suitable window case or the like, for supporting a shade roller in openings 3 formed in said bars, inwardly of the window case. At the inner ends of these shade roller brackets 1 are hingedly mounted a pair of bars 4 and 5 respectively, which are adapted to form drapery supporting members. These bars 4 and 5 are adjustably connected together, in overlapping relation, as indicated generally at 6. The bar 4 is formed with an offset or outstruck tongue portion 7, adjacent the free end thereof, which is adapted to extend through a slotted portion 8 extending longitudinally of the bar 5. The outer end of the bar 5 in line 110

with the slot 8 is formed with an offset portion 9 to permit the convenient insertion and removal of the tongues 7 to the inner slot of said bar. A pair of clamp members 10, of substantially C-shaped form, have their intermediate portions disposed between the tongue 7 and one face of the bar 5, for locking said bars in adjustable relation, in a manner clearly shown in Figure 3.

- 10 A pair of curtain supporting bars are indicated at 12 and 13 respectively, and are adjustably connected and constructed in the same manner as the bars 4 and 5, as indicated at 14. The outer ends of these bars 12 and 15 13 are provided with lateral extensions 15, having openings in the ends thereof for receiving links 16, adapted to extend through openings in the shade roller brackets 1, for suspension therefrom, and positioning outwardly of the drapery supporting bars 4 and 5.

With this construction, it will be seen that when the brackets are secured to the window casing, by means of the feet 2, the shade roller will be supported adjacent the window casing in the usual manner, while the curtains, such as lace curtains and the like, will be supported inwardly of the shade, by being suspended from the bars 12 and 13, 30 while the draperies, which it is desired to hang inwardly of the curtains will be secured to the bars 4 and 5, and depend therefrom over and inwardly of the curtain, and will conceal the supporting elements for the curtains and draperies. It will thus be seen that a simple and efficient construction has been made for suspending and mounting shade, curtain and draperies in relative spaced relation, so that the hanging of the 40 curtains will not interfere with the hanging of the draperies.

What is claimed is:

1. An adjustable shade and curtain

bracket comprising a pair of shade roller brackets adapted for attachment to a suitable support, a pair of drapery supporting bars adjustably connected together at their inner ends and pivotally secured to the shade roller brackets at their outer ends, and a pair of curtain supporting bars adjustably connected together at their inner ends and extended from the central portion of the shade roller supporting brackets for supporting curtains thereon, in spaced relation below and inwardly of the draperies. 45

2. An adjustable shade and curtain bracket comprising a pair of shade roller brackets adapted for attachment to a support, a pair of drapery supporting bars adjustably connected together at their inner ends and hingedly connected with said shade brackets at their outer ends, the adjustable connection being provided, by forming a slot in the end of one bar and an offset tongue struck out from the adjacent end of the other bar, and projecting through and 50 slideable in said slot, and locking members adapted to be positioned on said bars and to extend between the tongue and the slotted bar. 55

3. A window fixture of the class described comprising a pair of shade roller brackets, a pair of drapery supporting bars hingedly connected at their outer ends to said brackets, the inner ends of said bars being adjustably connected together, a second pair of curtain supporting bars adjustably connected together at their inner ends, each bar being provided with a vertical portion at its opposite end, and flexible connections 75 between the last named ends of the vertical portion and the intermediate portions of the aforesaid shade brackets. 80

In testimony whereof I affix my signature.

BEULAH L. RAINS.
